UNITED STATES PATENT OFFICE.

JOSEPH H. TILLINGHAST, OF SAN FRANCISCO, CALIFORNIA.

WOOL-SCOURING APPARATUS.

1,359,769.

Specification of Letters Patent. Patented Nov. 23, 1920.

Application filed February 18, 1920. Serial No. 359,584.

To all whom it may concern:

Be it known that I, JOSEPH H. TILLINGHAST, a citizen of the United States, residing at San Francisco, in the county of San Francisco and State of California, have invented new and useful Improvements in Wool-Scouring Apparatus, of which the following is a specification.

This invention relates to improvements in apparatus for facilitating the scouring of wool and like material.

The primary object of the invention is to provide apparatus for advancing wool through scouring baths in a reliable and expeditious manner, and so that large quantities of wool may be scoured effectively and quickly, much more so than when scoured with the apparatus now in use.

Another and more specific object of the invention is to provide apparatus for moving wool through liquid from one end of a receptacle to the other and then lifting said wool out of said liquid and depositing it upon a conveyer; the movement of the wool through the liquid being such as will provide for a thorough and expeditious scouring thereof.

The invention possesses other advantages and features, some of which, with the foregoing, will be set forth at length in the following description wherein I shall outline in full that form of the invention which I have selected for illustration in the drawings accompanying and forming a part of the present specification. In said drawings, I have shown one form of the construction of my invention, but it is to be understood that I do not limit myself to such form, since the invention as expressed in the claims may be embodied in a plurality of forms.

Referring to the drawings:

Figure 1 is a longitudinal fragmentary sectional view through a tank showing the apparatus of my invention in side elevation and partly broken and in section, and illustrating various positions of the apparatus in dotted lines.

Fig. 2 is a top plan view of the apparatus.

Fig. 3 is a sectional view taken on the line 3-3 of Fig. 1 with certain parts omitted for the sake of clearness of illustration.

Fig. 4 is a sectional view taken on the line 4-4 of Fig. 1, showing a part thereof broken away.

In carrying out my invention, I mount a reciprocating wool advancing member and

a wool lifting member on a tank or vat containing a scouring liquid and provide operating means which will move the advancing member to advance the wool into position to be engaged and lifted out of the tank by said lifting member, which latter member is operated in timed relation to said advancing member and deposits the wool lifted thereby upon a conveyer. The conveyer carries the wool into another tank to repeat the scouring operation. While I have shown one tank, it is to be understood that as many as desired may be used. The apparatus is preferably arranged so that the advancing member moves to advance the wool through the liquid, then lifts clear of the wool and moves back to starting position in a plane above the wool and then lowers into wool engaging position. Thus the wool is intermittently advanced into a position to be lifted out of the liquid by said lifting member and in being thus moved is thoroughly washed while advancing.

The present embodiment of my invention as illustrated in the accompanying drawings comprises a tank or vat 1 open on its upper side and containing a suitable liquid, not shown, for washing the wool. I have shown one tank, but in practice I employ several tanks contiguously arranged so that wool is moved through one and into the other. Mounted to reciprocate into and out of one end of the tank 1 is a wool advancing member 2 comprising a frame 3 which is preferably rectangular, horizontally supported, and of slightly less width than the space between the walls 4 of the tank whereby the frame extends substantially entirely across the tank or vat and may move freely between the walls. The frame carries a plurality of sets of spaced fingers or teeth 5, the sets preferably being secured to the under side of the frame as at 6 and depending therefrom at the ends and center of the frame 100 transversely thereof. These fingers extend across the tank and are slightly spaced from the bottom 7 of the tank when in operative position. The frame 3 is supported just above the level of the liquid which level is indicated by the line 8, whereby only the fingers are immersed in the liquid.

The frame 3 is suspended from a frame comprising uprights 9 secured on opposite sides of the tank and a cross piece 10 secured to the uprights. Depending from the cross piece, is a pair of hangers 11 having

bearings 12 in their lower ends for horizontal shafts 13 and 14 arranged side by side and operatively connected by gears 15 fixed to said shafts and meshing with each other. 5 Fixed to each shaft and depending therefrom are pairs of supporting arms 16 provided on their lower ends with rollers 17 which ride in guideways 18 therefor arranged on opposite sides of the frame 3. 10 The arms 16 normally extend downwardly, diverging from one another and thus support the frame 3 in horizontal position. Crossed arms 19 are fixed to the shafts 13 and 14 and extend upwardly therefrom carrying weights 20 thereon above the shafts. These weights are arranged to assist the mechanism in raising the member 2, to the dotted line position shown in Fig. 1. To provide for so raising the member 2 and for lowering it, a rocker arm 21 is fixed to the shaft 13 and extends substantially at right angles to the arms 16 carried by said shaft. This rocker arm is pivotally connected as at 22 with a reciprocating rod 23. 25 The rod 23 is operatively associated with the main operating mechanism, which will be later described, and when pulled will rock the arm 21 and rotate the shaft 13 and shaft 14 through the gears 15, causing the arms 16 to lift or raise the member 2 as will be later described more fully. The outer end of the rod 23 is provided with a series of spaced openings 24 which provide for adjusting the connection thereof with the arm 21 to regulate the height to which the member 2 is raised.

The member 2 is reciprocated and raised and lowered by operating means comprising a frame 25 in which is journaled a shaft 26. 40 Pulleys 27 are fixed to this shaft and support belts 27 driven from a suitable source of power, not shown. The shaft 26 has a pinion 28 thereon which meshes with a pinion 29 on a shaft 30 also journaled in the frame 25 and which extends across the tank 1. A preferably rectangular operating frame 31 is pivotally suspended from the shaft 26 by suitable means 32 which permits the frame 31 to swing back and forth. The 45 shaft 30 extends through the central point in said frame 31 and has an eccentrically mounted circular disk 33 fixed thereto so as to engage opposite longitudinal sides 34 of the frame, said frame being channeled to receive the eccentric 33. Thus as the shaft 30 and eccentric 33 rotate, the frame is swung back and forth as indicated in dotted lines in Fig. 1. This frame 31 in swinging back and forth provides for movement of the 55 wool lifting member 35 as to its body movement and also provides for reciprocation of the member 2. Rods 36 are pivoted at certain ends, as at 37, to the frame 3 of the member 2, and at their other ends are pivoted, as at 38, to arms 39 extending down-

wardly from and rigidly connected with said frame, whereby when the frame swings, the member 2 will reciprocate.

The wool lifting member comprises a shaft 40 rotatably mounted in a bearing 41 on the lower ends of the arms 39. Spaced tines or lifting fingers 42 are secured to the shaft 40 and extend outwardly at right angles thereto. The tines or fingers 42 are arranged to extend across the tank, as are the fingers 5, and normally lie in horizontal position, as shown in full lines in Fig. 1. To provide for rotation of the shaft 40 so as to effect a lifting of the wool with the fingers 42, a rocker arm 43 is fixed to the shaft 40 and has an adjustable pivotal connection 44 with a reciprocating swinging rod 45. This rod 45 is slotted as at 46 at its upper end and slidably and pivotally mounted on the shaft 30 by provision of such slot. A cam 47 is fixed to the shaft 30 and rotates so as to engage a roller 48 on the rod 45. A weighted arm 49 is fixed to the shaft 40 and has a tendency normally to rotate the shaft so as to move the tines 42 into down position, this tendency being normally overcome by the rod 45 and rocker 43, cam 47 and roller 48. The tines 42 during the operation of the machine are adapted to extend over a conveyor 50 as shown in dotted lines in Fig. 1, which is mounted between the wall 4 of the tank and leads to another tank not shown.

The means for reciprocating the rod 23 to raise and lower the member 2 comprises a cam 51 fixed to the shaft 30 and bearing upon a roller 52 carried on a slotted guide member 53. The guide member 53 is slidably connected upon the shaft and at one end is connected as at 54 to the rod 23. The other end of this member is bent back upon itself to provide a hook portion 55. The slot in the guide member opens out through this hook end whereby the shaft 30 enters and leaves this open end. The cam roller 52 is journaled in said hook end and when the cam rotates this roller in engaging the cam causes the guide member and rod 23 to be reciprocated.

The operation of the machine is as follows:

Wool is directed into one end of the tank 1 and submerged in the liquid therein, so that it will be scoured in being moved through the liquid. Assuming that the apparatus is in the position shown in full lines in Fig. 1, upon rotating the shaft 26, the shaft 30 is rotated in the direction of the arrow, shown in Fig. 1, by the gears 28 and 29 on the respective shafts. At this time, the cam 51 is in such position that when the shaft 30 begins to rotate, the rod 23 will be moved. The eccentric 33 effects a swinging of the operating frame 31 into the right hand dotted line position shown in Fig. 1 of the drawing. As the frame 31 swings to

the right, the wool advancing member 2 is moved to the right through the rod 36 connected with the hangers 39 and frame 3 respectively. Thus the wool advancing member 12 is advanced in a substantially horizontal plane and the wool in the tank in front of the fingers 5 will be pushed through the liquid, causing the liquid to circulate through the wool and effect a scouring action. After the shaft 30 and eccentric 33 have made one quarter of a revolution, the frame 31 has been swung to its outermost right hand position, as shown in dotted lines in Fig. 1, and the member 2 has been lifted so that the fingers 5 are clear of the liquid in the tank, as shown in dotted lines in said figure. The cam 51 is so shaped that in rotating against the roller 52 on the guide 53, said guide and rod 23 attached thereto will be moved to the right, such movement rocking the rocker arm 21 and rotating the shaft 13. By rotating the shaft 13, the gears 15 on the shafts 13 and 14 provide for rotation of the shaft 14 also, and the arms 16 are moved away from one another, causing the rollers 17 to move outwardly in the guideways 18 and the frame 3 to be lifted. The weights 20 on the arms 19 assist in the lifting of the frame 3 by exerting a tendency to rotate the shafts 13, 14, thus it will be seen that the wool advancing member 2 moves horizontally in the tank to advance the wool in front of the fingers 5 and is then lifted perpendicularly out of the tank after so advancing the wool.

As the shaft 30 continues to rotate, the member 2 is moved toward the adjacent end of the tank above the plane of its first movement and free from contact with the liquid in the tank back into starting position. The cam 51 maintains the member 2 in elevated position until the end of this backward movement of the member 2 is reached, at which time the cam engages the roller 52 so as to push the rod 23 and rock the arm 21 whereby the shafts 13 and 14 will rotate so as to cause the member 2 to descend into the tank into position to engage and advance the wool. At the time that the member 2 is descending into starting position the frame 31 has swung into its extreme left hand position, shown in dotted lines in Fig. 1 and the lifting member 35 has been brought into position to lift up the wool advanced by the member 2 during the previous advancing movement of said member 2. As said frame 31 swings to the left, the cam 47 moves so that the roller 48 which it engages will move freely over the cam so as to permit the rod 45 to move upwardly. This rod has a tendency to move upwardly at all times when the weight 49 is in up position, as shown in Fig. 1 of the drawings, and when the cam 47 permits said rod to move upwardly, the weight will gravitate and by so doing ro-

tate the shaft 30, so as to bring the fingers 42 from substantially horizontal position into substantially vertical position, such as shown in dotted lines in Fig. 1 of the drawings, and behind the wool advanced by said member 2. As the member 2 begins to advance horizontally through the liquid, the cam 47 bears upon the roller 48 so as to depress or push downwardly the arm 45 with the result that the shaft 40 is rotated so as to lift the tines or fingers 42 and when so lifting, the fingers will pick up the wool in front thereof. During this lifting up of the fingers, the frame 31 begins to swing back toward the right and this moves the fingers 42 bodily in an arc toward the right, while said fingers are being swung back into a normal horizontal position. With this operation, the fingers scoop up the wool and carry it forward so that when the frame 31 moves to its furthermost right hand position, said fingers will extend over the adjacent end of the conveyer 50 and deposit the wool lifted thereby on to said conveyer. At the time that these fingers extend over the conveyer 50, the roller 48 engages in a notched surface 57 on said cam 47 and the rod 45 is permitted to have a quick upward movement which results in causing the fingers 42 to snap downwardly upon the conveyer and the wool is thus quickly disengaged from the fingers immediately after this snapping down of the fingers 42 on the conveyer. The frame 31 is swung back toward the left, through action of the eccentric 33 and the fingers are moved clear of the wool and conveyer. It will thus be seen that the member 2 has a substantially rectilinear motion, in which it advances first horizontally in the tank and then lifts clear of the tank perpendicularly, moves back to starting position and then lowers perpendicularly back into the tank. This operation being continuous, the wool is advanced intermittently, and in being thus advanced, the liquid in the tank is caused to circulate through the wool in such a manner that effective scouring of the wool is supplied. The cam operating means is timed so that the lifting means may be brought into its various operating positions at the proper time to pick up the wool advanced by the member 2. The operating means is of simple compact form, utilizing comparatively little power to operate effectively. The operating means in view of its simplicity, and particular arrangement is reliable, positive in operation and capable of operating continuously without becoming deranged.

I claim:—

1. In wool scouring apparatus, a tank for containing a wool scouring liquid, a wool advancing member adapted to extend into the liquid and advance the wool therein, means for reciprocating said member, a

- frame, shafts rotatably mounted in the frame, arms fixed to said shafts and extending downwardly therefrom and diverging from one another, rollers secured to the lower ends of said arms and guideways on said member in which the rollers are slidably mounted, gears fixed to said shafts and meshing with one another, a rocker arm fixed to one shaft, a rod fixed to said rocker arm and means for reciprocating said rod.
2. In wool scouring apparatus, a tank for containing a wool scouring liquid, a wool advancing member adapted to extend into the liquid and advance the wool therein, means for reciprocating said member, a frame, shafts rotatably mounted in the frame, arms fixed to said shafts and extending downwardly therefrom and diverging from one another, rollers secured to the lower ends of said arms and guideways on said member in which the rollers are slidably mounted, gears fixed to said shafts and meshing with one another, a rocker arm fixed to one shaft, a rod fixed to said rocker arm and means for reciprocating said rod, crossed arms fixed to the shafts and extending upwardly therefrom and weights secured to the upper ends of said arms.
3. In wool scouring apparatus, a tank for containing a wool scouring liquid into which wool to be scoured is placed and a frame mounted above the tank, an operating frame swingingly supported in the frame, a rotary shaft extending through said operating frame, a circular disk eccentrically mounted upon said shaft and engaging opposite sides of said operating

frame, a wool advancing member mounted in the tank and a rod pivotally connected with the wool advancing member and the swinging frame.

4. In wool scouring apparatus, a tank adapted to contain a scouring liquid a frame extending above the tank, a rotary shaft in said frame, means for rotating said shaft, an operating frame mounted to swing back and forth on said main frame and through which the shaft extends, a circular disk eccentrically mounted on said shaft and engaging opposite sides of said operating frame, a bar depending from said operating frame, a shaft rotatably mounted on said bar a plurality of spaced lifting fingers fixed to said last-named shaft and means for rotating said shaft to move said fingers into and out of the liquid.

5. In wool scouring apparatus, a tank adapted to contain a scouring liquid, a frame extending above the tank, a rotary shaft in the frame, a wool advancing member reciprocably and vertically movably mounted in the tank, means operated when the shaft is rotated for raising and lowering said wool advancing member, a rotary shaft, supports for said shaft, a rocker arm fixed to the first-named shaft, a rod pivotally connected at one end with the rocker arm and slideable upon said second-named shaft, a cam fixed on said second-named shaft, a roller carried by the arm and engaged by said cam, and means operatively associated with the second-named shaft for reciprocating said wool advancing member.

JOSEPH H. TILLINGHAST.
